CLAIM

The ornamental design for a disposable hydration bladder, as shown and described.

DESCRIPTION

FIG. 1 is a front perspective view of an embodiment of a disposable hydration bladder, according to the claimed design.

FIG. 2 is a front view of the disposable hydration bladder shown in FIG. 1.

FIG. 3 is a rear view of the disposable hydration bladder shown in FIG. 1.

FIG. 4 is a right side view of the disposable hydration bladder shown in FIG. 1.

FIG. 5 is a left side view of the disposable hydration bladder shown in FIG. 1.

FIG. 6 is a top view of the disposable hydration bladder shown in FIG. 1; and,

FIG. 7 is a bottom view of the disposable hydration bladder shown in FIG. 1.

The features shown in broken lines are unclaimed portions of a disposable hydration bladder, and not part of the claimed design.

1 Claim, 5 Drawing Sheets
